Primary Examiner—Wallace R. Burke*Assistant Examiner*—Lisa Lichtenstein*Attorney, Agent, or Firm*—H. Neil Houser[57] **CLAIM**

The ornamental design for a downdraft vent unit for a cooktop, as shown and described.

DESCRIPTION

FIG. 1 is a top perspective view of a modular downdraft vent unit for a cooktop showing my new design; FIG. 2 is side elevational view thereof, the opposite side being a mirror image of that shown; and, FIG. 3 is an end elevational view thereof, the opposite end being a mirror image of that shown.

The broken-line showing of a cooktop in FIGS. 1-3, is for illustrative purposes only, and forms no part of the claimed design.
